UNITED STATES PATENT OFFICE.

JULIUS OTTO OBERMAIER, OF LAMBRECHT, BAVARIA, GERMANY.

APPARATUS FOR DYEING, BLEACHING, &c.

SPECIFICATION forming part of Letters Patent No. 332,740, dated December 22, 1885.

Application filed January 27, 1885. Serial No. 154,262. (No model.) Patented in Germany December 5, 1882, No. 23,117; in Denmark January 10, 1883; in Russia January 15, 1883, No. 5,434; in Spain January 24, 1883, No. 20,120; in Italy February 8, 1883, No. 15,091; in Austria March 6, 1883, No. 42,204, and in Sweden April 7, 1883.

To all whom it may concern:

Be it known that I, JULIUS OTTO OBERMAIER, a citizen of the German Empire, residing at Lambrecht, Bavaria, Germany, have invented certain new and useful Improvements in Apparatus for Treating Fibers, Yarns, and Weavings of all Kinds, of which the following is a specification.

The object of this invention is the dyeing, washing, and so forth, of textile fibers, yarns, and weavings of all kinds by the continuous circulation of the liquids ordinarily employed for these purposes through the matters to be so treated.

Figure 1 is a sectional elevation of an apparatus for effecting these objects and embodying my invention. Figs. 2, 3, 4, 5, 6, and 7 are merely modifications, in all of which figures the principle is unaltered.

The apparatus consists of two concentric perforated cylinders, C M, the inner or smaller one, C, being open below. The spaces between these cylinders serve for the reception of the textile material to be treated, which is piled up in equally-divided layers. The bottom is closed. The top is closed by means of a lid, P, which by means of a screw presses this lid more or less down upon the material to be dyed, in which condition it remains during this operation, it being by this means firmly pressed and immovable. The screwing-down arrangements are marked by the letters h, p, f, and F. The cylinder M having been filled with the textile matter it is hoisted by any suitable means and placed in the vat A, in which the dye has been previously prepared, and, if so desired, is heated by the introduction of steam. Beneath this cylinder is the inlet N of a continuous-acting suction and force pump, G, fixed beneath the vat A. This pump is set in motion and the liquid dye is drawn off from the vat A and forced into the small perforated cylinder C, and from thence through the layers of textile matter in the cylinder M that are to be dyed. The liquid then passes through the outer cylinder (which is also perforated) into the vat A and the process recommences.

K is a valve at the bottom of the vat. H is a drawing-off tap. R are heating-tubes.

When several operations are to be performed—such, for instance, as boiling the fibers, dyeing, mordanting, rinsing, &c.—a number of vats are placed side by side, and the vessel containing the textile matter is placed in each of these successively till the operations of boiling, dyeing, mordanting, rinsing, &c., are performed, as desired. By this means time is saved, and the contents of the different vessels for effecting these objects can be used for a longer period. This arrangement is subject to modifications according to the nature of the matters to be so treated, without, however, departing from the principle of action.

In Fig. 2 the cylinders C, mounted on the perforated upper plate of the chamber D, are closed by a perforated and adjustable lid, and the pump G, Fig. 1, or some equivalent, forces the liquid (intended to act on the textile matter) through the pipe a, whence it enters the cylinders at the bottom and makes its exit above. The chamber E beneath the intermediate one, D, is intended for the reception of other materials—such as wool, yarn, &c. This is closed by the perforated lid e.

In Fig. 3 the liquid being forced in at the bottom it makes its exit at the top b, as shown by the dotted arrows; or if the liquid is forced in at d it spreads first in the upper chamber above the perforated plate F, and then passes through the material piled up between F and E and runs off at the bottom, as shown by the solid arrows.

In Fig. 4 the cylinder C is not perforated, but has openings n, through which the liquid is forced up by the pipe a and passes through the perforated bottom of the cylinder M into the space E. The liquid then rises by pressure from the space E and passes through the material and flows out at the top through the perforated lid D.

In Fig. 5 the liquid is forced through the lateral tube d, where it enters (after passing through the material in the cylinder M) into the cylinder C, where it flows off.

In Fig. 6 the liquid is forced into the space C', and entering the perforated sides of the cylinder M passes through the material therein contained and flows off into the cylinder C.

5 In all these modifications the principle is unchanged.

So as to make the greatest possible use of the various liquids used for the dyeing, washing, &c., the arrangement shown in Fig. 7 10 (which is constructed on the same principle) is employed.

In the vat A two vertical cylinders, C' C², are placed, each one communicating with a pipe, a' a², connected with a suction and force 15 pump, G. The cylinders M M' being filled with textile matters which are pressed closely together, the pump G is then set in motion, and the dyeing-liquid being sucked up from the vat or reservoir A is then forced through 20 a² to C² and flows through the material in the cylinder M; but as the motion of the pump

reduces the pressure of the air in the cylinder C' the liquid in A passes rapidly through the sides of the cylinder M', as well as through the layer of material, and returns by a' to the 25 pump, whence it is again sucked and forced, as before described, so producing a continuous circulating action of the liquid.

What I claim is—

In an apparatus for treating textile fibers, 30 &c., the combination, with the vat, of the stationary perforated cylinder M, the interior stationary perforated cylinder, C, and the pump having connections with the vat and the central cylinder, substantially as described. 35

In testimony that I claim the foregoing as my invention I have signed my name in presence of two subscribing witnesses.

JULIUS OTTO OBERMAIER.
